Primary Examiner — Phillip S Hyder*(74) Attorney, Agent, or Firm* — Michael J. Smith(57) **CLAIM**

The ornamental design for a magnetic separation apparatus, as shown and described.

DESCRIPTION

[FIG. 1 is a top perspective view of an embodiment.]

[FIG. 2 is a side view of an embodiment.]

[FIG. 3 is a side view of an embodiment.]

[FIG. 4 is a side perspective view of an embodiment; and.]

[FIG. 5 is a side perspective view of an embodiment where two of the pieces have been separated.]

[No color is claimed as part of the design, nor are any logos, and/or written matter claimed as part of the design.]

*FIG. 1 is a top front and right side perspective view of a magnetic separation apparatus, showing my new design;
FIG. 2 is a cross section view taken along the line 2-2 of FIG. 1;
FIG. 3 is a side elevation view thereof;**FIG. 4 is a top front and left side perspective view thereof; and,**FIG. 5 is a top front and left side perspective view thereof wherein the components of the design are separated.**The broken lines depict portions of the magnetic separation apparatus in which the design is embodied that are not considered part of the claim design.***1 Claim, 4 Drawing Sheets****Matter enclosed in heavy brackets [ ] appears in the original patent but forms no part of this reissue; matter printed in italics indicates the additions made by reissue.**(56)
